UNITED STATES PATENT OFFICE: REISSUED

JOHN RINGEN, OF ST. LOUIS, MISSOURI.

DESIGN FOR A SAUCEPAN.

SPECIFICATION forming part of Design No. 16,566, dated March 9, 1886.

Application filed November 25, 1885. Serial No. 183,998. Term of patent 14 years.

To all whom it may concern:

Be it known that I, JOHN RINGEN, a citizen of the United States, residing in the city of St. Louis, State of Missouri, have invented and produced a new and original Design for 5 Saucepans, of which the following is a specification, reference being had to the accompanying drawing, forming part thereof, and which is a perspective view of my new design of 10 pan.

My design consists in a body, A, of heart shape in plan view, a bead-like figure, A', surrounding the bottom, a bead-like figure, A'', surrounding the upper portion beneath the top, 15 a depressed portion, C, at top, surrounded by a flat raised portion, C', an oblique arm, D, projecting from the rounded part B, and an arched strip, C'', in the center of the depressed portion, in line with the arm and point of the 20 body.

Three of these saucepans designed as de-

scribed and arranged as shown leave spaces D' between them.

Having thus described my design for a saucepan, the following is what I claim as of 25 my invention and production and desire to secure by Design Letters Patent:

The design for a saucepan herein shown and described, consisting of a heart-shaped body, A, in plan view, a bead-like projection, A', 30 surrounding the bottom, a bead-like projection, A'', surrounding the upper portion beneath the top, a depressed portion, C, at the top, a flat raised portion, C', surrounding the depressed portion, an oblique arm, D, projecting from the rounded part B, and an arched strip, C'', on the depressed portion, in line with the arm and point of the body.

JOHN RINGEN.
